United States Patent Office

Des. 202,091
Patented Aug. 24, 1965

202,091

PLASTIC SHEET MATERIAL OR THE LIKE

Virginia Broderick, Wauwatosa, Wis., assignor to Consoweld Corporation, Wisconsin Rapids, Wis., a corporation of Wisconsin

Filed Sept. 1, 1964, Ser. No. 81,542

Term of patent 14 years

(Cl. D87—3)

Fig. 1.

FIG. 2.

FIGURE 1 is a plan view of a plastic sheet material showing my new design wherein the design unit is repeated in regular succession as indicated by the extensions beyond the unit boundaries; and

FIGURE 2 is an enlarged plan view of the design unit, which constitutes the essential feature of my new design.

I claim:

The ornamental design for a plastic sheet material or the like, substantially as shown and described.
